CARBON PILE REGULATOR

William G. Neild, Fair Lawn, N. J., assignor to
 Bendix Aviation Corporation, Teterboro, N. J.,
 a corporation of Delaware

Application November 23, 1949, Serial No. 128,940

4 Claims. (Cl. 201—51)

1

The present application relates to improvements in a carbon pile regulator of the type disclosed in the copending U. S. application Serial No. 18,433, filed April 1, 1948, now Patent #2,533,038, issued December 5, 1950, by William G. Neild.

In carbon pile regulators of the type having a spring opposing the armature of an electromagnet, it is desirable that the spring have a force deflection curve that will closely approximate the pull of the electromagnet. For this reason, it is desirable that some means be provided for adjustment of the spring so that the force of the one matches that of the other.

An object of the invention is to provide improved adjustment means for the armature spring to vary the spring characteristic thereof to match the force of the electromagnet.

Another object of the invention is to provide an improved armature spring arrangement.

Another object of the invention is to provide a novel spring rate adjustment means whereby the rate of a compression spring may be adjusted to provide a regulation calibration in a carbon pile voltage regulator.

The above and other objects and features of the invention will appear more fully hereinafter from a consideration of the following description taken in connection with the accompanying drawings wherein three embodiments of the invention are illustrated by way of example.

In the drawings:

Figure 1 is a fragmentary view of a regulator showing the novel spring arrangement.

Figure 2 is a longitudinal section view of the regulator shown in Figure 1.

Figures 3 and 4 are fragmentary views of modified forms of spring arrangements.

Referring to the drawing of Figures 1 and 2, there is illustrated a carbon pile regulator of a type disclosed and claimed in my copending application Serial No. 18,433, filed April 1, 1948 and assigned to the assignee of the present application. The regulator includes a carbon pile indicated by the numeral 10 and comprising a number of hollow discs of carbon which are stacked within a tube 11. The tube 11 is preferably formed of a suitable ceramic or other electrical insulating material to carry away the heat developed by the carbon pile 10. The carbon pile 10 is of a suitable size and length to develop the desired regulating characteristics. The tube 11 is received within a metal shell 12 and, in order to facilitate the dissipation of the heat, the shell is preferably provided with fins 13 over its length so as to more readily dissipate the heat away

2

from the pile and increase the capacity of the pile. Only a fragmentary portion of the carbon pile 10, tube 11, housing 12 and fins 13 have been illustrated as they may be any of the types known to the art.

A contact element 14 is adjustably mounted within the tube 11 and has mounted thereon a button 15 which bears upon an engaging element 16 of an armature 17 for regulation of the carbon pile 10. The contact element 14 is regulated by the action of the armature 17 so as to vary the compressive force applied on the carbon pile 10 and accordingly the resistance thereof.

The armature 17 includes a flexible metal hinge 18 which has one end fastened to the armature 17 and the other end fastened by bolt 19 and bar 20 to one end of a U-shaped supporting member 21 having legs which extend at opposite sides of an electromagnet 22. The electromagnet 22 is fastened by bolts 23 to a supporting plate 24. The bolts 23 also serve to secure the U-shaped member 21 to the plate 24. Screw-threadedly engaged in the plate 24 is an adjustable electromagnetic core 25, which projects through the electromagnet 22 into operating spaced relation to the armature 17. The plate 24 is fastened to the shell 12 by rods 26.

While one end of the armature 17 is flexibly connected by the hinge member 18, the opposite end of the armature 17 is operatively connected to a spring mechanism indicated generally by the numeral 27 and of the type disclosed and claimed in my copending application Serial No. 684,379, filed July 17, 1946, now U. S. Patent No. 2,506,234, and assigned to the assignee of the present application.

The mechanism 27 includes a ball 28 which rides at one side in a seat 29 carried by the armature 17, while the opposite side of the ball 28 rides in a seat 30 formed in an adjustable member 31. The member 31 has projecting therefrom a stem portion 32 having screw threads 33 which engage in corresponding internal threads formed in a member 34. A lock nut 35 serves to fasten the stem 32 in adjusted position relative to the member 34. The member 34 extends at a ninety degree angle to the plate 24. One side of the member 34 is fastened by bolts 36 to one end of a curved metal spring blade 37. The other end of the spring 37 is fastened to a block 38 by screws 39. At the opposite side of the member 34, there is fastened by nut 40 of bolt 36 one end of a similar curved metal spring blade 37. The opposite end of the latter spring 37 is fastened to a similar block 38 by screws 39.

A novel feature of the present application resides in the arrangement of the blocks 38 which are adjustably secured to the plate 24 by screws 41 extending through slotted holes 42 in the plate 24 to engage threaded portions of the block 38.

The blocks 38 each have a longitudinal bore 43 extending throughout the length thereof and adapted to receive a bolt 44 having a nut 45 on the end thereof.

A further feature of the disclosure of the present application resides in the provision of an adjustable means to prevent the armature 17 from coming into contact with the magnetic core 25. This means is in the form of a non-magnetic screw 46 adjustably mounted in the armature so as to provide a stop to limit the air gap between the armature and electromagnet. The adjustable screw 46 provides a convenient means for calibrating the air gap between the armature and magnetic core and eliminates the heretofore known expedient of providing shims of non-magnetic material of varying width to limit the minimum air gap.

Further, in operation by adjusting the position of the nut 45 on the bolt 44, the positions of the blocks 38 are altered in respect to each other. Varying the position of the blocks 38 varies the ends of the springs 37, and in so doing, changes the radius of curvature at the preformed bend in the springs. This change in radius produces a change in the spring rate (the unit deflection per unit loading) thus making proper calibration of the regulator possible. After the blocks 38 are adjusted, the spring 37 is preloaded by means of the adjustable stem 32. With the blocks 38 adjusted for the desired calibration upon a force being applied to the armature 17 by the electromagnet 22, the springs 37 will tend to wrap or roll on the surface of the vertical member 34 and blocks 38 as the armature 17 moves under the force of electromagnet 22. Such action will decrease the radius of the springs 37 and greatly increase its resistance to force, so as to provide a force deflection curve which very closely resembles an inverse square curve and effect a rolling non-slipping action with a minimum friction.

The latter force deflection curve will closely approximate that of the electromagnet 22 which will apply a force to the armature 17 which continuously increases in excess of a linear relation as the armature 17 approaches the electromagnet 22 and which force will vary approximately inversely as the square of the distance between the armature and magnet. Thus the opposing armature spring 37 is arranged to compensate for the varying force applied by the electromagnet 22 to the armature 17. Basic correspondence between the forces of the spring 37 and the electromagnet 22 may be effected by adjusting the blocks 38 to change the radius of the springs so that the force of the springs match that of the electromagnet.

A modified form of the spring arrangement is shown in Figure 3 in which corresponding numerals indicate like parts to those described in Figures 1 and 2.

In the arrangement of Figure 3, one end of a spring 47 is secured to armature 17 by screw 48. The other end of the spring 47 is secured to a block 49 by screw 50. The block 49 is supported by a bolt 51 extending through a longitudinal bore 52 in the block 49. The bolt 51 extends through a longitudinal bore 53 in a block 54. The block 54 is secured to an L-shaped bracket 55 by bolts 56. The bracket 55 is adjustably mounted on one leg of the U-shaped member 21 by means of screws

57 extending through slotted holes 58 in the bracket 55. A nut 59 on the bolt 51 permits adjustment of the blocks 49 and 54 relative to each other thus changing the radius of the spring 47. Pins 60 prevent rotation of the block 49.

Another modification of the spring arrangement is shown in Figure 4 in which corresponding numerals indicate like parts to those described in Figures 1, 2 and 3.

In the arrangement of Figure 4, one end of a U-shaped spring 61 is fastened to the block 49 by the screw 50. The other end of the spring 61 is fastened to the block 54 by a screw 62. The blocks 49 and 54 are mounted in a similar manner as described in reference to Figure 3. Adjusting the nut 59 changes the radius of the spring 61 thus producing a change in the spring rate.

In operation, the springs 47 and 61 wrap upon the armature 17 and blocks in substantially the same manner as the spring 37 previously described.

Although only three embodiments of the invention have been illustrated and described, various changes in the form and relative arrangements of the parts may be made to suit requirements.

What is claimed is:

1. In an electrical regulator of the type including a variable electrical resistance means, an electromagnet, an armature movably mounted in relation to said electromagnet, means connecting the armature to the variable electric resistance means; the improvement comprising a spring mechanism including a supporting member, a pair of block members adjustably mounted on said supporting member, a movable member operatively connected to said armature and extending at a substantially ninety degree angle relative to said supporting member, curved spring blades connected at opposite ends to said movable member and to said respective block member and arranged so that upon movement of said armature toward said electromagnet said curved spring blades wrap upon said movable member and said respective block member so as to decrease the radius of the curved blades and progressively increase the resistance of the spring blades to the displacement of said armature by said electromagnet, means for adjusting said block members to vary the radius of said curved springs to vary the force characteristic of the spring blades.

2. The combination defined in claim 1 and including adjustable means operatively connected to said movable member to preload said armature.

3. For use in an electrical regulator of the type including a variable electric resistance means, an electromagnet, an armature movably mounted in relation to said electromagnet, means connecting the armature to the variable electric resistance means, said electromagnet biasing said armature in a direction for changing the electrical resistance of said variable electric resistance means; a spring mechanism comprising at least one curved blade spring, a movable member, a base member, one end of said spring being secured to said movable member, the other end of said spring being adjustably connected to said base member for axial movement relative to said movable member to vary the radius of said curved spring blade, said spring blade being so arranged that upon movement of said movable member in one sense said curved spring blade wraps upon said base member and said movable member so as to decrease the radius of the curved blade and progres-

sively increase the resistance of the spring blade to displacement of said member in said one sense.

4. For use in an electrical regulator of the type including a variable electric resistance means, an electromagnet, an armature movably mounted in relation to said electromagnet, means connecting the armature to the variable electric resistance means, said electromagnet biasing said armature in a direction for changing the electrical resistance of said variable electric resistance means; a spring mechanism comprising at least one curved blade spring, a movable member, a base member, one end of said spring being secured to said movable member, the other end of said spring being adjustably connected to said base member for axial movement relative to said movable member to vary the radius of said curved spring blade, said spring blade being so arranged that upon movement of said movable member in one sense 20

said curved spring blade wraps upon said base member and said movable member so as to decrease the radius of the curved blade and progressively increase the resistance of the spring blade to displacement of said member in said one sense, and including means for adjusting one of said members to preload said spring blade.
